ERNEST C. CROCKER, OF BELMONT, MASSACHUSETTS, ASSIGNOR, BY MESNE ASSIGNMENTS, TO THE LANE COMPANY, INC., A CORPORATION OF VIRGINIA

METHOD OF AROMA TESTING OF CEDAR CHESTS

Application filed July 18, 1930. Serial No. 468,980.

While I have, for the purpose of illustrating my invention, selected what is known to the trade as a cedar chest, it is, of course, obvious that my invention may with equal efficiency be embodied in wardrobes, chifforobes, closets, household furniture, and other receptacles designed for the destroying of the clothes moth larvæ found in clothing, furs, and similar articles stored in such receptacles.

From experiments, conducted over quite a long period the object of which was to produce a cedar chest that would destroy the clothes moth larvæ, I discovered the fact that aroma thrown off by the aromatic cedarwood oil, found in aromatic cedar was effective in killing moth larvæ of any age if the proper concentration could be developed, and I have also found that the two fundamentals in securing proper concentration of aroma are to get enough cedarwood oil into the chest which I am accomplishing by introducing enough cedar lumber to supply this oil and by making the chest sufficiently aroma tight.

By preventing this leakage and putting enough oil in the chest I could get enough concentration to kill moth larvæ of any age and that all of this prevents the necessity of having to have clothes cleaned to get them free of moth eggs and larvæ, or beaten, or brushed, or sunned, all of which methods have been recommended by various authorities to free fabrics of moth infestation. The old type of cedar chest which was not aroma tight, according to United States Government recommendations, would kill newly hatched moth worms up to half grown (three months old) but if a person would place any fabrics into a chest that had more than half grown moth worms on them, they were so hard to kill that the cedar aroma concentration in the chest was not strong enough to kill them, but this I have been able to accomplish with my new aroma tight chest. The problem which I desired to work out was to destroy the moth larvæ present in such articles, or hatching from eggs, that might have had deposited on them when they were stored away, as it has been difficult and expensive and, in fact, impractical, to so clean every article stored as to insure the non-existence

of moth larvæ or moth eggs when the article was stored away.

Experiments demonstrate the fact that the aroma of the cedar oil, which is in fact cedar oil in a highly gaseous or vapor state, suspended in the air, is extremely penetrating and that, if the article infested with moth larvæ could be maintained in a receptacle for a sufficient length of time where the cedar aroma was of sufficient density, all moth larvæ would be completely destroyed. The problem, therefore, was to first obtain a sufficient amount of cedar oil aroma, next to imprison this aroma in the receptacle so that the article would remain in an atmosphere of cedar aroma of sufficient density the required length of time to destroy the moths, and, second, to so imprison and maintain the basic supply of cedar oil that the required density of aroma would be supplied over a long period of years to make the receptacle continuously effective.

It was found by experiment that cedar aroma, that is cedar oil molecules in suspension in air, is approximately seven times as heavy as air. Consequently it is more dense at the bottom of the receptacle and, of course, when the receptacle is closed the giving off of the cedar oil molecules creates in the receptacle a vapor or gaseous pressure which, although slight as pressures are ordinarily measured, is quite sufficient to cause the cedar aroma to escape from the receptacle through any hole, crevice or crack. And, while it will escape more rapidly from a hole at the bottom of the chest, as the density is greater at the bottom, this pressure created as heretofore explained, will cause it at certain stages to escape regardless of the location of the leak. Leakage or escape of the aroma from the chest is also caused by the variation in temperature in the room outside as compared to the air within the chest. I ascertained the approximate amount of cedar oil in the average red cedar board by dry weight and constructed the chest with the proper amount of red cedar for each cubic inch of storage space. This will give a sufficient quantity of cedar oil to produce aroma of sufficient density to be effective in destroying

moths, provided the density of the aroma could be maintained, leakage prevented and the escape of the cedar oil in the form of aroma could be largely confined to the inside of the chest so that it might not be wasted by escape outside into the room.

I also found that this percentage of red cedar to the cubic content of a receptacle would not only supply an aroma of sufficient density to destroy moths, but that it would continue to supply it over a long period of years, provided as above, that leakage and waste were prevented.

My experiments conducted over many years have proven that the moth killing efficiency of a cedar chest is proportionate to the amount of cedar oil present in the closure and the aroma tightness of the closure.

In the drawings:

Figure 1 is a perspective view of a cedar chest embodying my testing apparatus.

The apparatus for the aroma testing of cedar chests consists of cheese cloth sheets 1, coated with about 5% of their weight of common rosin (colophony) suspended within the chests. While I have specified cheese cloth, and common rosin, I reserve the right to use other agencies equally efficient and the percentage given may be varied within reasonable limits.

The thus treated cheese cloth sheets are then placed in a cedar chest, preferably suspended, and the chest closed.

The cloths are weighed from time to time during the test, to note how rapidly they pick up cedar aroma. I customarily record this increase in weight as 15, 28, 40, or what not milligrams per day for the cloths. It has been my observation that fatty, waxy, and resinous materials were active in absorbing the aroma of cedar wood from the air spaces of cedar chests, and that common rosin is the most active and consistent absorbent for cedar aroma, and that common rosin, dispersed over a cloth is an eminently practical and convenient means for absorbing cedar aroma from the air spaces of chests in such quantity that the aroma density therein may readily be measured.

By means of my apparatus and method, manufacturers of cedar chests are enabled to test their chests for efficiency and probable duration of efficiency and sell them with a guarantee of efficiency and duration of efficiency.

What I claim is:

1. In the method for the aroma testing of cedar chests the step which consists in coating a textile fabric with approximately 5% of its weight of colophony and placing said coated fabric in the chest and closing the chest.
2. In the method for aroma testing of cedar chests the step which consists in applying to a textile fabric approximately 5% of

its weight colophony, placing said treated fabric in a cedar chest and closing the chest.

3. The method for aroma testing of cedar chests which consists in applying to a textile fabric approximately 5% of its weight colophony, placing said treated fabric in a cedar chest and closing the chest, and removing the fabric from the chest from time to time and weighing it. 70

4. The method of aroma testing of cedar chests which consists in applying to a textile fabric approximately 5% of its weight colophony, placing said treated fabric in a cedar chest and closing the chest, removing the fabric from the chest from time to time and weighing it. 75

5. The method for testing of cedar aroma testing of cedar chests, which consists in applying to a textile fabric colophony, suspending said treated fabric in the cedar chest, closing the chest, weighing the fabric and noting from time to time the amount of cedar aroma picked up by said treated fabric. 85

6. The method for testing of cedar aroma of cedar chests which consists in coating a textile fabric with approximately 5% of its weight with rosin, suspending said coated fabric in a cedar chest, weighing the fabric, closing the chest, and noting from time to time the amount of cedar aroma picked up by said treated fabric. 90

7. The method for testing of cedar aroma of cedar chests, which consists in using cheese cloth sheets, coating said sheets with about 5% of their weight with rosin, suspending the sheets within the chest, weighing the fabric, closing the chest, and noting from time to time how rapidly said sheets pick up cedar aroma. 100

In testimony whereof I affix my signature. 105
